UNITED STATES PATENT OFFICE.

SATTERLEE ARNOLD, OF BROOKLYN, NEW YORK, ASSIGNOR TO ANNA M. ARNOLD, OF SAME PLACE.

SEWING-MACHINE.

SPECIFICATION forming part of Letters Patent No. 331,106, dated November 24, 1885.

Application filed May 14, 1884. Serial No. 131,487. (No model.)

To all whom it may concern:

Be it known that I, SATTERLEE ARNOLD, a citizen of the United States, residing at Brooklyn, in the county of Kings and State of New York, have invented certain new and useful Improvements in Sewing-Machines, of which the following is a specification, reference being had therein to the accompanying drawings.

My invention relates to that class of sewing-machines in which the needle-bar and needle have lateral movements at right angles, or nearly so, to the line in which the work is moved or fed, the needle thus descending at different times in different vertical planes for the purpose of forming irregular, ornamental, or zigzag stitches, or, in other words, stitches crossing the line of movement of the fabric being sewed.

In the present embodiment of my invention the needle is caused to make three stitches in one lateral direction and then three stitches in the opposite lateral direction, the special object of my invention in this instance being the production of a machine for uniting the abutted edges of knit or other fabrics by a smooth and substantial seam, thus producing a garment without a ridge or welt at the line of union of the pieces of fabric of which it shall be composed, the stitches crossing and recrossing said line of union, and being connected to the body of the fabric at either side thereof.

Instead of causing the needle to make three stitches in one lateral direction and then three stitches in the opposite direction, as above referred to, the mechanism for moving the needle laterally may be so constructed as to impart alternate right and left movements to the needle to form zigzag stitches, which will be desirable with much of the work for which my machine is specially intended.

As my machine in the form shown in the accompanying drawings is more especially designed for sewing tubular goods—such as stockings, &c.—the work-plate is made in the form of an arm or horn adapted to enter such tubular articles as they are being sewed. It is, however, obvious that for other classes of work a flat work-plate of the ordinary construction may be employed, when desirable, with the stitch-forming mechanism, which I will hereinafter describe.

In the annexed drawings, forming a part of this specification, Figure 1 is a perspective view of my improved sewing-machine. Figs. 2 and 3 are side views of the same. Fig. 4 is 55 a plan or top view. Fig. 5 is a plan view, partly in section, on the line xx , Fig. 2, showing the looper-rod and its connections. Fig. 6 is a detail view in perspective of the looping-hook and a portion of the looper-rod. Fig. 60 7 is an under side view of the cloth-plate. Figs. 8 and 9 are views of the shuttle, the latter being a section on line zz of the former. Fig. 10 is a view of the gearing, partly in section. Fig. 11 is a perspective view of the 65 means for actuating the needle-bar frame. Fig. 12 is a perspective view of the front portion of the machine. Figs. 13, 14, and 15 are detail views of the feeding mechanism. Fig. 16 is a perspective view of the presser-foot. Fig. 70 17 is a perspective view of the needle-bar, and Fig. 17^a a cross-section of the same. Fig. 18 is a skeleton view of the needle and looper mechanisms. Fig. 19 is a perspective view of the needle-bar frame. Fig. 20 is a top end 75 view of the same. Fig. 21 is a side view showing the relative positions of the needle, shuttle, and looping-hook at the moment the latter throws the thread-loop over the pointed end of the shuttle; and Fig. 22 is a similar 80 view with the take-up added, showing the hook about to disengage itself from the loop.

A indicates the bed or work plate of the machine, which in the present instance is made narrow and somewhat tapering toward 85 its forward end to form an arm or horn. The rear portion of the bed-plate is shown as being provided with a perforated flange, A², and the machine can thus be secured to the work-table by suitable screws passing through said 90 flange. The arm or horn A is hollow or recessed for the reception of the stitch-forming mechanism co-operating with the needle, and is covered by a plate, preferably made in sections 1 and 2, the section 2, which may be 95 formed the "cloth-plate," being cut away for the reception of a removable plate or shuttle-cover, 3, and a throat or needle plate, P. The removable plate 3 can be taken out when access to the shuttle is necessary, and the throat 100 or needle plate can also be removed when worn, or when it is desired to insert a throat-

plate having a needle-opening of different form.

Formed integral with or secured to the rear end of the bed-plate is the goose-neck or bracket-arm B, which is made somewhat longer than usual, the forward end of said bracket-arm having a depending portion or head, which sustains the frames carrying the needle-bar and the cloth pressing and feeding mechanisms.

10 The bracket-arm B is shown as a plain frame flanged or ribbed for strength, and provided with a plurality of lugs or brackets to afford bearings for the levers and shafts constituting the operating mechanism of the machine; but

15 instead of the form shown said bracket-arm may be so constructed as to afford a housing for said operating mechanism, in which case the side of the arm will preferably be provided with a removable covering-plate to afford ready access to the interior of the arm.

Journalized in bearings in the rear portion of the bracket-arm B is a vertically-arranged driving-shaft, C, having at its upper end a fast pulley, C², and a loose pulley, C³, onto either of which, by means of a belt-shifter, C⁴, a driving-belt connected with power may be run. An eccentric, 4, is secured upon the driving-shaft C, adjacent to the loose pulley C³, said eccentric being surrounded by a strap 30 formed integral with or secured to a pitman, 5, the forward end of which has a ball-and-socket connection with the short arm of a primary lever, E, pivoted on a stud, E², secured to the bracket-arm B. The forward end 35 of the long arm of the primary lever E is connected by a link, 6, (see Figs. 2 and 18,) with the short arm of a secondary lever, F, pivoted on a stud, F², entering the bracket-arm B, the forward end of the long arm of the lever F being attached to a link, 7, which in turn is connected to a stud, 8, secured to the needle-bar 9, said needle-bar carrying at its lower end the usual eye-pointed needle. The link 7 has ball-and-socket connections with the lever F 40 and stud 8, to form a loose joint between said lever and needle-bar. The needle-bar 9 is adapted to reciprocate vertically in lugs or bearings 10, formed upon or secured to a frame, H, which latter, by means of vertical pivots 45 connected with lugs 26* on the said frame H and the forward end of the bracket-arm B, (see Figs. 12 and 19,) is adapted to swing horizontally, carrying with it the needle-bar and needle, which will thus be moved laterally for the 50 purpose of forming stitches across the line of the movement of the work.

The mechanism which moves the needle-bar laterally will be described further on.

As my machine is intended to be run at very 60 high rates of speed, it is essential that all of the moving parts should be made as light as possible consistent with proper strength; and to this end the needle-bar (the movements of which consume a considerable part of the power used in driving the machine) is flattened and grooved on opposite sides, said grooves being preferably concave in cross-section, as

shown. By constructing my needle-bar in this manner a considerable portion of the metal is cut away, while, owing to the ribs left at its corners, the strength of the needle-bar is not greatly diminished. The openings in the lugs 10, through which the needle-bar passes, are conformed in shape to a cross-section of the needle-bar, and firm bearings for the latter are thereby secured, while the shape of said bar effectually prevents any such axial movement thereof as is liable to occur with cylindrical needle-bars. The lugs 10 are preferably formed in two parts, the outer or removable parts being secured to the inner or fixed parts by screws passing through the former into the latter. Owing to the outward pressure of link 7, the latter will naturally bear the needle-bar outward, and as a result of this tendency the wear of the needle-bar will occur mostly against the outer or removable parts of the lugs 10. When sufficient wear has occurred to occasion any looseness, the caps or outer portions of the lugs 10 can be removed, and by properly dressing down the inner faces of said caps the looseness occasioned by wear may be taken up, and thus the proper positions of the main bearings for the needle-bar will be maintained.

It will be apparent that the construction thus described affords large bearing-surfaces for the needle-bar in proportion to the size of the latter, and at the same time prevents any axial movement or deflection of the needle-bar.

On the vertical driving-shaft C is a worm, D, said worm being preferably placed loosely on said shaft, so that it can slide up and down thereon, and when thus loosely mounted it is caused to rotate therewith by a spline or feather connection. The worm D, when loosely mounted on said shaft, is formed with upper and lower screw-cam surfaces, 38, (see Fig. 2,) engaged by anti-friction rollers 39, mounted on small brackets 40, which latter are rigidly secured to the arm B. The screw-cam surfaces are conversely arranged, so that they are both in constant contact with the rollers 39, and as the shaft C rotates said screw-cam surfaces, working between said rollers, will cause the worm D to reciprocate longitudinally of said shaft, effecting one back-and-forth movement at each revolution of the latter.

Journalized in a frame, 34, (see Figs. 3 and 11,) rigidly secured to the arm B, is a worm-wheel, 33, engaging, through an opening in said arm, with the worm D. Owing to the sliding movement of the worm D on the shaft C, said worm will impart an intermittent rotary movement to said worm-wheel, moving the latter to the extent of one tooth at each revolution of the shaft C. If the driving-shaft be turned in the direction indicated by the arrow in Fig. 4, this movement of the worm-wheel will take place when the worm is rising, the worm-wheel remaining stationary while the worm is descending, the threads of

- the worm, during the descending movement of the latter, traveling idly through the teeth of the worm-wheel. If the pitch of the threads of the worm should be reversed, or 5 the shaft C should be turned in a direction opposite that indicated by the arrow in Fig. 4, the worm-wheel would remain at rest when the worm was rising, and would receive its movement when the worm was descending.
- 10 The worm-wheel 33 serves the double purpose of giving rotary movement to the feeding-wheels and imparting lateral movements to the needle-bar frame and needle-bar, the movements of the feeding-wheels and needle-bar being (in the form of my invention herein set forth) intermittent, so that they can occur when the needle is out of the fabric. One face of the worm-wheel 33 is formed with a series of face cams or corrugations, 32, each 15 of these face-cams, from the center of one depression to the center of the next depression, being just equal in extent to six teeth on the worm-wheel. A lever, 31, pivoted near its center to the arm B, is provided at one end 20 with a toe-piece, 41, which bears against the face-cams 32 of the wheel 33, the opposite end of said lever being jointed to a rod or link, 30, pivoted at its forward end to a lug, 27, (see Fig. 19.) on the needle-bar frame H.
- 25 30 To vary the throw of the needle-bar frame H, the lever 31 may have several holes, (see Fig. 11,) to permit the rod or link 30 to be attached thereto at different distances from the fulcrum of the said lever.
- 35 The rod or link 30 is preferably made in two pieces, as shown, the two pieces being so connected that the rod may be shortened or lengthened at will to secure a proper adjustment of the parts, thus permitting the needle-bar and needle to be adjusted to bring the latter into proper position relative to the needle-plate and feed-wheels. In the present instance the two parts of the rod 30 are connected by a block, which is fixed to one part 40 of the rod, and is provided with a socket and set-screw, by means of which the other part of the rod may be adjustably secured thereto. A block or sleeve tapped with right and left hand screw-threads, with screw-threaded ends 45 on the adjacent parts of the rod, might be used to accomplish the same result. A strong plate-spring, 11, bears against one of the lugs 10 on the needle-bar frame H, said spring having a tendency to move said needle-bar 50 frame in opposition to the movement imparted thereto by the rod 30 and lever 31, and the said spring, by acting through the frame H, rod 30, and lever 31, also serves to keep the toe-piece 41 on said lever in contact with the 55 face-cams 32.
- 60 Instead of forming face-cams on the worm-wheel, a cylinder having a serpentine cam-groove of proper form might be employed, said cam-cylinder being formed integral with 65 or secured to the worm-wheel or its shaft. In such case a pin or roller-stud on the lever 31 would enter said cam-groove, and said lever
- would be moved positively in both directions, thus obviating the necessity of the spring for securing the return movements. A shaft, 61, 70 (see Fig. 3,) is caused to rotate with the worm-wheel 33 by a screw or pin passing through the hub of said wheel and loosely engaging a groove, 63, in said shaft. A feed hanger-frame, M, is loosely attached to the forward end of 75 the bracket-arm B by screws passing through slots 37 in said frame into said bracket-arm. Said frame carries the feeding-wheels 65 and presser-foot 66, and is arranged to be lifted by a cam-lever, 51, engaging a lug or arm thereon, and is yieldingly held upon the work passing beneath the feeding-wheels and presser-foot by a spring, 47, attached to an arm, 45, of said frame, and to a loop or stud, 48, secured to the lower forward portion of the bracket- 80 arm.
- 85 By means of the construction just described it is obvious that the feeding-wheels and presser-foot may be held upon the work or raised therefrom, as occasion may require. The shaft 90 61 has a bearing at its forward end in a projection, 49, of the feed hanger-frame M. The forward end of said shaft is provided with a small beveled gear-wheel, 60, meshing with a similar gear-wheel, 59, on the upper end of a 95 vertical shaft, 58, journaled in bearings 56 57 on the frame M. A beveled gear on the lower end of the shaft 58 engages a similar gear, 62, (see Fig. 15,) on a horizontal shaft, 54, arranged within a block, 52, forming the lower 100 portion of the hanger-frame M.
- To the shaft 54 is secured a wide gear-wheel, 55, meshing with both of the feeding-wheels 65, (see Fig. 14,) which are provided on their peripheries with teeth engaging the 105 gear-wheel 55 and the fabric. The feeding-wheels are arranged at acute angles to each other and to the line of movement of the work, and as they converge rearwardly they will have a tendency to press the abutted edges of 110 fabric toward each other, thus insuring their close contact. The feeding-wheels 65 are separately journaled in arms 64, adjustably secured to the block 52 on the frame M by screws 36, passing through slots 35 into the 115 said block. By means of this slotted connection with the block 52 the arms 64, and with them the feeding-wheels 65, may be arranged nearer to or farther from each other, and by slightly swinging said arms 64 on the screws 120 36 as pivots the angles of the inclination of the feeding-wheels may be adjusted to meet the requirements of the work being performed, and as these arms are adjustable independently of each other either one or both of said 125 feeding-wheels may be adjusted at the pleasure of the operator. Of course when the arms 64 are to be adjusted the screws 36 will be loosened slightly, and they will be tightened again to properly secure said arms after the 130 adjustment has been made.
- It has been found that the ordinary four-motion feed does not always work satisfactorily with knitted goods, as they are thin and so

elastic that they will sometimes stretch when engaged by the feed, and will thus fail to be properly moved to form the stitches, and to avoid this difficulty the wheel feed, which always has a positive hold upon the goods, has been found advantageous. This kind of feed is particularly desirable in a machine in which the needle has a lateral movement, requiring a slotted throat-plate, as the continuous positive engagement of the feed-wheels with the fabric obviates the tendency of the latter to crowd into the slot in the throat-plate, the fabric being kept under a constant tension at the sewing-point.

I am aware that it is not new to arrange a feeding-wheel above the work-plate. I am also aware that two feeding-wheels arranged on opposite sides of the needle have been heretofore employed; but in such instance said feeding-wheels were below the work-plate, and were so placed that their axes were opposite to the sewing-point, or the line in which the needle reciprocated. In my machine the feeding-wheels are journaled slightly in advance of the needle, so that they push rather than pull the goods forward, and this pushing avoids stretching the fabric, and assists in causing the abutted edges to be closely pressed together at the sewing-point, where they are to be united by the stitch-forming mechanism. As the feeding-wheels are turned slightly outward, this arrangement somewhat in front of the needle or sewing-point is not apparent in those figures of the drawings in which said wheels are viewed from their outer sides. This feature is, however, shown in Fig. 14, which is somewhat exaggerated to make this point clear. The presser-foot 66 is secured to the block 52 by a screw, 38, said screw passing through a slot, 39, in the vertical arm of said presser-foot to provide for vertical adjustment. On its under side the presser-foot is formed with two grooves, 67, (see Fig. 16,) converging toward each other as they approach the needle-slot 40, where they end. This construction of the presser-foot assists in guiding and bringing together the abutted edges of the fabric.

To the lower end of the vertical driving-shaft C is secured a crank-disk, 68, (see Figs. 2 and 3,) carrying a crank-pin connected by a link, 69, with a similar crank-pin on an arm, 70, on the upper end of a secondary vertical shaft, 71, which shaft is journaled to the arm B in a different vertical plane from that of the driving-shaft C, so that the axes of the two shafts are out of line. By this arrangement and connection of these two shafts a differential rotary movement will be imparted to the shaft 71 from the driving-shaft C. In other words, while these two shafts will rotate coincidentally, or will both perform a single revolution in the same time, the shaft 71 will move much more rapidly during one portion of its revolution than it will during the other portion. The shaft 71 is provided on its lower end with a crank, 72, (see Figs. 5

and 18,) to which is secured a looper rod or lever, 73, sliding through and turning in a swiveled bearing, 74, and having at its front a looping-hook, 75. The looper-rod 73 is preferably formed in two pieces adjustably secured together, so that said rod may be lengthened or shortened, as may be necessary, to bring the looper in proper position relative to the needle and shuttle. The swiveled bearing 74 is located considerably forward of the center of the looper-rod, so that the looper on the front end of said rod will be caused to travel in an elliptical path, which is somewhat more flattened at one end than at the other, as indicated in Fig. 5. The shuttle 76 (see Figs. 8 and 9) is stationary, and is loosely supported in a holder, 77, (see Fig. 7,) arranged in the interior of the forward end 85 of the arm or horn A, on which the work is supported. Said shuttle is provided with a bobbin, 78, of ordinary construction, for carrying the locking-thread, and with a tension-bar, 79, around which said thread is wound a sufficient number of times to insure the proper degree of tension.

The take-up consists of a bell-crank lever, I, (see Figs. 1 and 2,) pivoted on the stud F², which serves as a fulcrum for the lever F. The long arm of the lever E is provided at its forward end with a plate, 17, said plate being preferably slotted, so that it may be adjustably connected with said lever. The plate 17 is joined by a link, 18, with the short arm 19 of the take-up lever I. By adjusting the plate 17 on the lever E it is obvious that the movements of the take-up lever I may be properly timed and adjusted.

To the take-up lever I is secured a light supplementary spring take-up, 20, which is confined in its upward movement to the take-up I by a loop, 21. Eyes 22 23, for the passage of the thread, are provided at the lower ends of the take-up lever I and supplementary take-up 21. The thread passes from the spool 24 around a tension-bar, G, of ordinary construction, and through guide-eyes 25 and 26 on the forward end of the arm B. From the guide-eye 26 the thread is carried upward through the eye 22 in the end of the take-up lever I, then to the eye 23 in the end of the supplementary take-up, whence it passes downward through an eye on the lower needle-bar guide, 10, to the eye of the needle.

The links 6, 7, 18, and 69 are all split, or formed in two pieces, each link having at each end a spherical cavity or socket fitting on a ball-stud on the respective parts or devices to be connected by said links. By this construction positive but free and loose connections between the various parts are secured.

As the two parts of the links are secured together by screws, they may be separated and the adjacent faces filed away to take up any wear which may occur in the spherical sockets.

The operation of my machine is as follows: Motion being given to the driving-shaft, the

eccentric 4 thereon, through the connecting-rod 5, primary and secondary levers E and F, and links 6 and 7, imparts a reciprocating movement to the needle-bar. In the present instance the relative arrangement and connection of the levers E and F are such that the well-known double reciprocating or "dip" movement will be given to said needle, the upward movement for the second descent being very small. This dip movement, however, is not essential, as in the construction shown the looper or hook 75 seizes the loop of needle-thread on the first descent of the needle; but it is essential that the needle, before it makes its final ascent, should pause a sufficient length of time to enable the looper or hook to carry the loop of needle-thread around the point of the shuttle, and to do this before the needle rises the said looper or hook must move with great rapidity after it has caught the loop of needle-thread. The looper or hook 75 is operated by means of its connections with the shaft 71, which, as before explained, has a differential movement, the rapid portion of its revolution commencing when the said looper or hook is about to catch the loop of needle-thread, and continuing while it is carrying said loop around the point of the stationary shuttle 76, after which time the slower movement of the shaft occurs, causing the looper to slacken its speed to enable the take-up to draw the thread entirely around the shuttle and its interlocking thread, and to tighten and thus complete the stitch. The rapid movement of the looper or hook when passing the needle insures the engagement of said hook with the developed loop of needle-thread. Thus the operation continues, the stitches being repeated indefinitely while the machine runs. As soon as the loop of needle-thread has been carried around the point of the shuttle by the looper or hook 75, and has become disengaged from said looper or hook as the latter backs or travels away from said loop, the supplementary take-up spring 20, which has been drawn down by the rapid expansion of the loop, suddenly reacts and pulls the thread quickly around the shuttle and out of the way of the advancing looper before the main take-up 1 rises to complete the stitch. The supplementary take-up 20 also serves to keep the thread from slackening during the first part of the descent of the needle-bar, thus holding the thread out of the way of the point of the needle. The upward movement of the supplementary take-up is limited by the loop 21, as before explained. The traveling or lateral movements of the needle-bar and needle across the line of the feed are produced by the face-cams 32 on the worm-wheel 33, through the lever 31 and rod 30, the latter being connected to the swinging needle-bar frame H. The return movement of said frame and of its connections to the face-cams is induced by the plate-spring 11. As the worm-wheel 33 is moved to the extent of one tooth only at each revolution of the driving-shaft, and as each face-cam on said

worm-wheel, in the form of my invention herein shown, has a sectoral length equal to six teeth on said wheel, it follows that six descents of the needle will occur and six stitches thus be formed while each one of said face-cams is traveling over the toe-piece 41 of the lever 31. The upward and downward slopes of the face-cams 32 are equal, and three stitches will be formed while the toe-piece is riding upward and three while it is riding downward on each cam. From this it will necessarily result that the needle-bar will move laterally in one direction during three stitches, and laterally in the opposite direction during three succeeding stitches. The first of each of these series of stitches will be formed in the fabric entirely on one side of the line of union of the abutted edges, thus constituting an anchoring-stitch. The second will extend across the line of union, and the third will be an anchoring-stitch in the fabric on the side of the abutted edges opposite to the first. In returning, the needle will make a similar series of three stitches running in the other direction. As the feeding mechanism herein shown and described will have continually advanced the goods at each stitch, and as the traversing movements of the needle-bar and needle are nearly at right angles to the line in which the work is moved, each series of three stitches will be diagonal to the line of union of the abutted edges. The anchoring-strokes above referred to are necessary to form a strong seam in knitted goods, which are of a loose and elastic character; but the number of stitches in each series may be varied with the character of the work by changing the form and sectoral extent of the face-cams 32 on the worm-wheel 33, as will be obvious to those skilled in the art to which my invention relates. Thus, if it is desired to form plain zigzag stitches, which will be desirable with much of the work for which my machine is specially adapted, the cams 32 on the wheel 33 will occur at the alternate teeth of the said wheel, so that the swinging needle-bar frame and the needle-bar carried thereby will receive short horizontal movements, causing the needle to descend alternately in two different vertical planes. It will be observed by reference to Fig. 5 that the forward part of the path traversed by the looper or hook 75 is nearly an exact semicircle. The pivot-pins securing the swinging needle-bar frame to the forward end of the arm B are arranged as nearly as possible in a vertical line coincident with the center or point from which the semicircular path traversed by the looper or hook is described. By this arrangement the needle, as it moves laterally, will be confined to a curved path coincident with that described by the looper or hook 75, and it will therefore not be displaced from its proper operative relation to the looper by its lateral movements. The ball-and-socket connections of the link 7 with the needle-bar and its operating-lever F per-

mit the needle-bar to be moved laterally with its frame H and still retain its proper connection with said lever. The feeding-wheels, with the operating mechanism herein shown, 5 receive an intermittent rotary movement from the worm-wheel 33 through the shafts 61, 58, and 54 and their connected gearing, the feeding movement occurring, as in most other machines, when the needle is out of the work. 10 The feeding-wheels being arranged slightly in front of the needle or sewing-point, the work is pushed along, the converging arrangement of the wheels serving to press the abutted fabrics closely together, as heretofore explained. 15

I do not wish to confine myself to the specific mechanism herein shown and described, as many changes within the province of mechanical skill may be made without departing 20 from the spirit of my invention. It will also be understood that parts of my invention may be used independently of other parts, if desired, or with other mechanisms serving the purpose of the mechanisms which I have 25 shown. For example, my special feeding mechanism might be used with a different kind of stitch-forming mechanism, or the stitch-forming mechanism with a different kind of feed.

30 The mechanism for moving the needle-bar and needle laterally, with the modification here before suggested, might be employed in machines for working button-holes or over-seaming; also, instead of the lock-stitch mechanism herein shown and described, different devices co-operating with the needle to form chain or other kinds of stitches might be used in connection with the other features of my invention. The lock-stitch mechanism 35 is, however, preferred for the class of work for which this machine is specially intended, as with this form of stitch the seam is alike on both sides of the fabric, and will not rip to any appreciable extent should the threads 40 accidentally be broken. I do not, however, claim, broadly, in this application many of the features of my invention, as they are reserved for other applications.

The needle-bar and its bearings and the 45 looper mechanism constitute the subjects-matter of applications Nos. 131,489 and 131,488, respectively, filed simultaneously herewith. The feeding mechanism and the shuttle are embraced by my applications Nos. 136,233 and 50 136,234, respectively, filed June 28, 1884.

Having thus described my invention, I claim as new and desire to secure by Letters Patent--

1. In a sewing-machine, the combination of 55 a bracket-arm, primary and secondary needle-operating levers loosely connected together and having long and short arms, the said long arms extending horizontally along said bracket-arm, a needle-bar loosely connected with the forward end of the long arm of the 60 said secondary lever, and mechanism for operating said levers, substantially as set forth.

2. In a sewing-machine, the combination of a driving-shaft having an eccentric thereon, a pitman connected with said eccentric, primary and secondary needle-operating levers loosely connected together and with said pitman, a swinging needle-bar frame, mechanism for vibrating said frame, and a needle-bar mounted in said frame and loosely connected with the forward end of said secondary lever, substantially as set forth. 70 75

3. In a sewing-machine, the combination of a driving-shaft, an eccentric thereon, a pitman connected with said eccentric, primary and secondary needle-operating levers, a link for connecting said levers, a swinging needle-bar frame, mechanism for vibrating said frame, a needle-bar mounted in said frame, and a link having ball-and-socket connections with said 80 needle-bar and said secondary lever, substantially as set forth. 85

4. In a sewing-machine, the combination of a needle-bar, a swinging frame in which said needle-bar is mounted, a worm having a thread 90 of a uniform pitch, a worm-wheel provided with a series of face or side cams, a lever engaging said cams, and a rod connecting said lever with the said swinging frame, substantially as set forth. 95

5. In a sewing-machine, the combination of a needle-bar, a swinging frame in which said needle-bar is mounted, a worm-wheel having a series of face or side cams, a lever engaging said cams, and a longitudinally-adjustable rod 100 connecting said lever with said swinging frame, substantially as set forth. 105

6. In a sewing-machine, the combination of a needle-bar, a swinging frame in which said needle-bar is mounted, a worm-wheel having 110 a series of face or side cams, a lever operated by said cam-wheel, and a rod attached to the said swinging frame and adjustably connected with the said lever, substantially as set forth. 115

7. In a sewing-machine, the combination of a needle-bar, a swinging frame in which said bar is mounted, a worm-wheel having a series of cams, mechanism through which said cams move said swinging bar laterally, and a feeding mechanism connected with and thus receiving its movement from said worm-wheel, substantially as set forth. 120 115

8. In a sewing-machine, the combination, with a needle-bar and mechanism for reciprocating said bar vertically and horizontally, of a stationary shuttle, a looper for carrying the needle-thread around said shuttle, and mechanism for imparting a circular movement to said looper in a horizontal path, substantially 125 as set forth.

9. In a sewing-machine, the combination of a driving-shaft, a needle-bar, primary and secondary needle-operating levers connected with said shaft and needle-bar, a secondary shaft 130 having its axis in a different plane from that of the said driving-shaft, and thus receiving a variable rotary motion therefrom, a stitch-forming device co-operating with the needle

carried by the said needle-bar, and connections for operating said co-operating stitch-forming device from said secondary shaft, substantially as set forth.

5 10. In a sewing-machine, the combination of a needle-bar, a vertically-pivoted needle-bar frame, mechanism for swinging said frame horizontally on its vertical pivots, a stitch-forming device co-operating with the needle carried by the said needle-bar, and means for moving said co-operating stitch-forming device, when adjacent to the said needle, in a curved path corresponding to that in which the needle is moved when the needle-bar frame and needle are swung laterally, substantially as set forth.

15 11. In a sewing-machine, the combination, with a hook or looper adapted to co-operate with the needle in forming stitches, and means for moving said hook or looper in a circular path when near the needle, of a needle-bar and a needle-bar frame, the latter mounted on pivots which are arranged as nearly as possible in a plane coincident with the point from which 20 the arc of the circle in which the said hook or looper moves when adjacent to the needle is described, so that the latter in its lateral movements will follow the curvature of the path in which the said hook travels when on that side 25 of its orbit which is nearest the needle, substantially as set forth.

20 12. In a sewing-machine, the combination of a needle-bar, mechanism for reciprocating the same vertically and horizontally, a feeding mechanism arranged above the work-plate, a stationary shuttle placed beneath the work-plate, and mechanism for carrying the needle-thread around said stationary shuttle, substantially as set forth.

25 13. In a sewing-machine, the combination of a driving-shaft, a secondary shaft connected with said driving-shaft and having its axis in a different plane from the axis of the latter, a hook or looper, connections between the said 30 hook or looper and the said secondary shaft, a stationary shuttle, a needle-bar, mechanism for reciprocating said bar vertically, a needle-bar frame, mechanism for vibrating said frame horizontally, a feeding mechanism, and means 35 for imparting the proper movements to said needle-bar, needle-bar frame, and feeding mechanism from the said driving-shaft, substantially as set forth.

14. In a sewing-machine, the combination of a needle-bar, mechanism for reciprocating the same vertically and horizontally, feeding and take-up mechanisms arranged above the work-plate, a stationary shuttle placed beneath the work-plate, and mechanism for carrying the needle-thread around said stationary shuttle, substantially as set forth.

55 15. The combination of a stitch-forming mechanism comprising a needle-bar, mechanism for reciprocating said bar vertically and horizontally, a slotted throat-plate to accommodate the horizontal movements of the needle carried by the said bar, two feeding-wheels arranged above the work-plate and on opposite sides the said needle, and mechanism for operating said feeding-wheels, substantially as 60 set forth.

65 16. The combination of a stitch-forming mechanism comprising a needle-bar, mechanism for reciprocating said bar vertically and horizontally, two feeding-wheels arranged 70 above the work-plate and at an angle to the movement of the work, and mechanism for operating said feeding-wheels, substantially as set forth.

75 17. The combination of a stitch-forming mechanism comprising a work-plate, a needle-bar, mechanism for reciprocating said bar vertically and horizontally, two feeding-wheels arranged above the said work-plate, and a presser-foot placed between said feeding-wheels, substantially as set forth.

80 18. The combination of a stitch-forming mechanism comprising a work-plate, a needle-bar, mechanism for reciprocating said bar vertically and horizontally, a bracket-arm, a feed 90 hanger-frame supported by said arm above the work-plate, feeding-wheels carried by said hanger-frame, gearing, also carried by said hanger-frame, for operating said feeding-wheels, and a spring connected with said 95 hanger-frame and a fixed part of the machine, for yieldingly holding said wheels against the work-plate, substantially as set forth.

In testimony whereof I affix my signature in presence of two witnesses.

SATTERLEE ARNOLD.
